Fig. 4

FIGURE 1 is an elevational view of a container for dairy products or the like showing my new design;

The side of the container not shown is the same as the side shown.

The dominant features of my design reside in the portions shown in full lines.

This application is a continuation of application Serial

Number D. 68,208 filed January 8, 1962, now abandoned.

I claim:

The ornamental design for a container for dairy products or the like, substantially as shown and described.
